CABLE SHEATH CUTTING KNIFE

Dwight D. Stone, Quincy, Mass.

Application February 28, 1946, Serial No. 650,802

18 Claims. (Cl. 30—91)

1

My present invention relates to cutting tools of the blade or knife type, with special but not exclusive reference to longitudinally slitting and transversely cutting the protective armor or sheath of electric conductor cables in preparing them for installation. More particularly the invention aims to provide for such purpose a knife having capacity for precision setting to any necessary depth of cut over an extensive range and whereby, with a known depth of armor for a given cable, the appropriate depth setting may be predeterminedly set selectively and with certainty of precision and accuracy, in making adjustments involving extremely small increments of depth variation.

These and other objects and advantages will be apparent from the following description in connection with the drawings, in which:

Fig. 1 is a side elevation with parts in vertical section, illustrating one typical embodiment of a cable knife in accordance with the invention;

Fig. 2 is a top plan view of the central tool-holding turret and setting means, with the cover cap of Fig. 1 omitted for clarity;

Fig. 3 is a vertical section showing details of the connection and release means at one side of the top plate, that at the right in Fig. 1;

Fig. 4 is a vertical section as on the line 4—4 of Fig. 1, further showing the parts concerned in Fig. 3;

Fig. 5 is a view mainly in top plan, as looking down on the tool of Fig. 1, but with the turret in horizontal section substantially on the line 5—5 of Fig. 1;

Fig. 6 is a side elevation of the tool as a whole with parts broken away at the top and with the lower plate and connecting means demounted;

Fig. 7 is a bottom plan view of the lower or bed plate, as viewed from below in Fig. 1;

Fig. 8 shows the cutter blade or knife and its holder bar separately in side elevation, this unit being turned 90° from its position as seen in Fig. 1;

Fig. 9 is a partial sectional view, on a smaller scale, showing certain cable guiding means, the view being in side elevation as if looking from the right on the Figs. 1 and 6; and

Fig. 10 is a bottom plan of the knife head or turret.

Referring to the drawings in more detail, my precision cable knife as there shown comprises opposed supporting elements or plates adjustably spaced to receive a cable between them. Noting particularly Fig. 1, these include a base plate or work-supporting bed 1 and a top plate or table 2. The cutting instrument or knife 3 is mounted on the top plate 2 through the medium of novel turret-like positioning, guiding and indexing means to be described. The work bed 1 and the knife table 2 are releasably and variably

connected by posts 4 and 5 at the opposite sides of the device.

The connector post 4 at the left, see also Figs. 5 and 7, is shown as a screw pivoted at its lower end as at 6 between ears 7 on the bed plate 1, so that it may be swung to and from engagement with the top plate 2, the latter slotted as at 8, Fig. 5, to receive it. Desirably a spring 9 at the lower end of the post 4 urges it toward the closed or upright position as in Fig. 1.

Referring particularly to Fig. 1, also Figs. 5 and 6, quick-releasable clamping engagement as between the post 4 and the top plate 2, in any vertically adjusted position of the latter, is provided. For this purpose the threaded portion of the post, which extends substantially its entire length, carries a knurled or other positioning and clamping nut 10 having a collar portion 11 receivable in the slot 8 of the top plate 2. The underface of the nut 10 is flat centrally and has a bevelled marginal portion as at 12 for cooperation with a latch 14 spanning the slot 8 and pivoted at one end on the top plate 2 as at 15, Fig. 5. An intermediate portion of the latch 14, Fig. 5, has an inwardly open slot 16 adapted to align with the slot 8 of the top plate 2 so that the latch may be swung horizontally by its projecting fingerpiece 17, to and from enclosing relation to the post 4 and beneath the adjusting nut 10, Fig. 1, as indicated by the full and the dotted line positions in Fig. 5.

As seen in Figs. 5 and 6, inclined cam formations as at 18, 19 at the respective sides of the latch slot 16 enable the latch readily to enter beneath the nut 10 (Fig. 1) by engaging the bevelled underportion 12 of the latter and lifting it together with the post 4 into position for receiving and retaining the latch between it and the upper face of the top plate 2. In the closed position as in full line in Figs. 1 and 5, a flat upper face of the latch 14 bordering its slot 16 seats firmly beneath the flat central underface of the nut 10.

In Fig. 1, the bed and top plates 1 and 2 are shown in relatively widely spaced relation, as set up for working on a cable of large diameter, approaching the maximum for which the particular size of tool is designed. In this connection it will be understood that the invention may be embodied in tools of various different sizes and with different overall range of adjustment as may be best suited to a particular field of service, as for example power transmission cables, as contrasted with leaded telephone cables, or with radio and radar cables, and the various other types and use classifications. Approximate maximum, minimum and intermediate cable diameters for which the illustrated knife may be used are indicated by the three broken-line circles at the lower central portion of Fig. 1. Typical cable-diameter ca-

facilities for a wide range model such as in Fig. 1, again by way of illustration only, are from say .300 in. through 2.875 in. diameter.

The Fig. 1 plate adjustment being as for a large cable, as noted, the positioning and clamping nut 10 accordingly stands adjacent the free upper end of the post 4. But whatever the particular size adjustment may be, it will be seen that when once set for a given cable diameter the movable post 4 may then be released and subsequently reengaged, to shift the tool or to remove it from one cable or portion thereof and to install it on another like cable or portion, merely by manipulating the latch 14.

In this connection means desirably is provided for releasably locking the clamping nut 10, Fig. 1, in any selected position of adjustment along the post 4. For this purpose there is associated with it a flanged lock nut 20 having a skirt 21 adapted to be turned down into locking engagement with the upper end face of the clamping nut 10. Preferably means is included whereby in the unlocked position the two nuts 10 and 20 are automatically spaced to avoid interference one with the other in changing the setting, yet are operable as a unit. Accordingly the clamping nut 10 has a pin 22 projecting at its upper face while the lock nut 20 has a cooperative pin or screw 23 at its under face. A coil spring surrounding the skirt 21 of the lock nut tends to space the two nuts and facilitate adjustment. The pins 22 and 23 being disposed in the same path circumferentially of the nuts provide in effect a lost-motion connection between the two. As viewed in Fig. 1, turning the lock nut 20 to the right (counterclockwise as viewed from above in Fig. 1) will cause pin 23 to swing around until it engages pin 22 on the adjusting nut 10, taking 10 with it, for adjustment of the device to accommodate a larger cable. For adjustment to a smaller cable size, turning the adjusting nut 10 to the left causes pin 22 to engage pin 23 on the lock nut 20 to cause it to follow. The adjusting nut 10 is locked in any position by turning nut 20 to the left.

At the other side of the tool, Fig. 1, the adjustable connection between the lower and upper plates 1, 2 may be generally similar to that as already described. Preferably however the connector element 5 is fixed relative to the bed plate 1 and is associated with the upper table 2 in a manner permitting rapid adjustment of the latter toward and from the bed plate 1 to any desired extent. Accordingly as illustrated the member 5 is formed as a slide, of rectangular cross-section through a major portion of its length. The lower end of this slide or guide 5 is rigidly connected to the corresponding lateral portion of the bed plate 1, as by extension through an aperture therein laterally opposite the pivoted clamp post 4, the lower preferably rounded end of the guide 5 having a retaining screw 26 and an anchor nut threaded on it as at 27. The corresponding side portion of the upper plate or tool table 2 comprises a centrally divided bracket including spaced arms 28, 29, Fig. 5, pivotally receiving between them a slider block 30. A removable pivot pin 31 extends through aligned bearing apertures in the plate arms 28, 29 and through a corresponding aperture in the slider 30. The connective pivot pin 31 may be demountably held in place as by spring rings 32, 33 received in annular grooves at the respective ends of the pin.

The slide block 30 has a vertical aperture 30a

(Figs. 3 and 5) affording it a sliding fit on the connective guide post 5, for selective positioning along it. Removable stop means such as a cotter pin 5a, Figs. 1, 4 and 5, at the free end of the post 5 defines an upper limit for the block 30 and prevents unintentional separation of the block and the post. This slide block 30 is adapted to be positively locked in selected position along the guide post 5, herein by a manually releasable and automatically locking means. Said means as illustrated, noting particularly Figs. 1, 3, 4 and 5, comprises a spring plunger 35 slidably received in a lateral recess in the slider block 30 and having a knurled head or other gripping piece 36 at its outer end. The plunger 35 is urged inwardly toward the guide post 5 as by a spring 37 bearing between an annular shoulder 38 adjacent the inner end of the plunger and a removable cover plate 39 on the block 30. Along the outer face of the guide post 5 is a series of selective plunger-receiving recesses 40 in closely spaced relation, any one of which is adapted to receive the plunger and thereby positively lock the block 30 in the corresponding selected position along the guide post 5 and hence to space the corresponding side portions of the lower and upper plates 1, 2 in correct operative relation to the particular size of cable.

For automatically locking the plunger or oppositely holding it in retracted position, the cover piece 39 on the block 30 has a lateral flange 42, Figs. 1, 3 and 4, the outer edge of which is formed with an inclined cam formation 43 having a locking notch as at 44 adjacent its outer or high portion. The outer portion of the plunger 35 carries one or more radial projection 45 receivable in the locking notch 44, to hold the plunger retracted and to ride along the cam 43 under the influence of the plunger spring. By retracting the plunger and slightly turning it to place one of the projections 45 against the cam the plunger will automatically be caused to move in to locking engagement with the nearest recess of the series 40 and the tool plate 2 are adjusted lengthwise the guide post 5.

It will be understood that to install the tool in operative relation to a cable, as for example the relatively large cable for which the device is set up in Fig. 1, the bottom-pivoted post 4 is unlatched and swung out free of the tool table 2. By retracting the plunger 35 the slide block 30 together with the table 2 may be freely shifted along the slide post 5 to any necessary extent. In the example of Fig. 1 the block 30 is thus moved toward the upper end of the slide post 5 to an approximate position as estimated to be correct for the given cable. The plunger is then released with respect to the locking notch 44, so that its spring in conjunction with the described cam 43 causes the plunger to lock into an adjacent hole of the series 40. The clamp nut pair 10, 20 are turned out to an approximately corresponding position along the swingable post 4. With the latch 14 open, the device as a whole is applied about the cable C, the latter entering at the opening between the out-swung post 4 and the table 2. The closing spring 9 automatically swings the post 4 into the open slot 8 of the said table. The latch 14 is thereupon closed about the sleeve 11 of the clamp nut 10. If it is found that some adjustment is needed for the opposite side of the table 2, as between it and the slide post 5, such is then readily effected by manipulation of the plunger 35 in the manner

explained, the latter automatically relocking into an adjacent recess of the series 40. The clamp nut 10 is then turned down until the tool runs freely but not loosely through the guides, in this instance the wheels 130—131, Figs. 1, 6, 9, and 10. The lock nut 20 is then turned to locking position. Having thus set up the work-holding parts for operation on the given cable size C, the tool as a whole may be thereafter released and again engaged with respect to the cable merely by opening and closing the latch 14.

From the foregoing it is evident, particularly with reference to Fig. 1, that the pair of adjustably spaced plates 1 and 2 together with the connecting means 4, 5 and associated parts as above described provide in effect an enclosure or frame adapted to be installed in surrounding relation to a cable. One of the plates, herein the bottom or bed plate 1 is provided with positioning means engageable with the cable, while the opposite plate, herein the upper plate or table 2, is adapted to present the cutting tool or knife 3. The tool holding means, herein in the form of a turret-like head is constructed and arranged for presenting the knife 3 for operative travel lengthwise the cable so as to slit the protective armor or sheath thereof along a line paralleling the cable, or optionally to present the knife in a transverse position for cutting the cable armor or sheath circumferentially. Correspondingly, the cable-engaging element of the opposite or bed plate 1 also is adapted for cooperative engagement with the cable either longitudinally or transversely of the latter.

Accordingly the bed plate 1 Figs. 1 and 7 is centrally recessed to form a bearing seat for a carrier or disk 50 rotatably positioned therein. This disk is demountably held against vertical displacement as by means of a cover plate 51 of larger diameter than the recess in the bed plate 1 and seating flatwise against the top face of the latter. This plate is assembled to the carrier disk 50 as by means of a plurality of screws 52 extending up through the disk 50 and tapped into the plate. Stop washers 53 on the screws and of a size to overlap the underface of the bed plate 1 hold the carrier disk 50 against upward displacement. The disk has a central through aperture as at 54 for housing the cable engaging roller 55 in and upon this carrying disk. Opposed intermediate portions of the side walls of the roller-housing aperture are formed with bosses 56, 56, see Fig. 7, between which the hub 55a of the roller 55 is received. These bosses are apertured in line to provide bearings for the roller shaft 57. Thus the roller 55 is mounted to rotate freely about the horizontal axis of its shaft 57, while the roller-carrying disk or cage 50 is in turn angularly adjustable about a vertical axis so as to present the roller for rotation in a vertical plane either paralleling the cable axis or transverse to it. The roller and its carrier are releasably held in either adjusted position by suitable means herein comprising a ball detent 58 Fig. 1 positioned in a radial recess in the bed plate 1 and urged inwardly toward the roller carrier as by a coil spring 59 bearing between the ball and bottom of its recess. The peripheral wall of the carrier disk 50 has generally V-shaped seating recesses 50a positioned to come opposite and receive the ball detent 58, so as to receive and retain the latter against the pressure of the rather stiff spring 59. In the illustrated example, four such ball seats are represented spaced 90°, so that a quarter turn of

the roller carrier 50 in either direction will serve to shift the roller 55 from one to the other of its operating positions and automatically retain it therein. Desirably the roller 55 has centrally about its peripheral surface a relatively soft metal or other insert 55x opposite the knife blade 3, to avoid dulling or injuring the latter through carelessness or mishandling.

Referring now more particularly to Figs. 1, 5 and 6, the tool-holder element or knife head herein comprises a generally cylindrical housing member or turret 60 having a central bore in which the tool or knife 3 is adjustably held and from which it is projected to variable extents and by accurately predeterminedly selectable increments of any degree of fineness, through the medium of the novel indexing means to be described.

Accordingly the upper plate or table 2 is formed with a central bearing recess 2a disposed axially in line with the center of the seat for the roller carrier disk 50 of the bed plate 1. The turret 60 has an annular bearing portion 61 having a snug bearing fit in the aperture 2a of the table 2. A peripheral flange 62 on the turret above said bearing portion 61 fits on and provides direct bearing support for the turret at the upper face of the table 2. Below the latter the turret has an annular groove 63 removably receiving a spring retaining ring and end thrust bearing member 64. The turret 60 is thus demountably but securely held on the table 2 with capacity for angular adjustment about the turret axis. It is releasably held and positively locked in different positions of angular adjustment, to present the knife 3 for operation lengthwise or transversely of the cable, as by means of a spring-pressed plunger 65 having a manipulating head 66; see Fig. 5. The plunger is urged inwardly by a spring 67 bearing between a shoulder at the inner portion of the plunger and a plate 68 screwed or otherwise demountably secured at one side face of the table 2, the plunger and its spring being housed in a recess formed in the table for the purpose. The annular bearing portion 61 Fig. 1 of the turret has a plurality of plunger-receiving sockets 61a Fig. 5 at the several quadrants of the turret, spaced similarly as for the described locking recesses of the roller carrier 50. Thus the turret together with the knife 3 housed therein may be turned in either direction in adjusting the knife as between longitudinal and transverse cutting operations, irrespective of which position it chances to be in at the time such adjustment is desired similarly as previously explained in connection with the cable roller 55.

The direct holding element for the knife 3 Figs. 1, 5 and 8 comprises an elongated lead screw or knife-holder bar 70. The inner or lower portion of this knife holder member 70 is of rectangular cross-section as at 71 Figs. 5 and 8 adapting it for accurate guidance and lateral support in the like-shaped rectangular lower portion of the turret bore, as at 60a, Fig. 1. The inner squared end 71 of the lead screw or knife-holder bar 70 is vertically slotted as at 72 Fig. 5 to receive the tang 3a of the knife 3, Fig. 8. The knife is demountably secured on its holder bar 70 as by means of a screw 73. Noting Figs. 5 and 8, the lower portions of the holder bar at opposite sides of the tang-receiving slot are apertured in line, the aperture at one side of the knife being tapped to receive the threaded end of the screw while the other side is countersunk to receive the screw head. The knife

tang 3a is apertured in line with the recesses, for passage of the attaching screw, the latter adapted to be turned up tightly to clamp and firmly anchor the knife with respect to the squared guide portion of its holder bar 70. Above the squared portion 71, Figs. 5 and 8, the knife bar is externally threaded as at 75, preferably fully to its outer end, for knife depth adjustment over a wide range. This threading desirably is lefthand, so that clockwise turning of the cooperative like-threaded adjusting nut member 80 to be described and which engages the bar thread 75 will cause descending adjustment of the knife, and correspondingly counter-clockwise turning of the nut will lift the knife.

Longitudinal adjustment of the knife 3 toward and from the cable position so as precisely to determine the depth of slice or cut of sheath, is herein effected by means of a longitudinally fixed, rotary adjusting and setting nut 80, having threaded engagement with the knife bar 70. Noting Figs. 1 and 6, this adjusting member 80 is centrally disposed in and rotatively supported at the upper portion of the turret 60, where it is held against movement in the axial direction. This nut 80 comprises an elongated sleeve-like member 81 including a tubular lower portion having intermediate its ends a down-facing annular shoulder 82 and at its upper end an enlarged head 83 desirably including wings 84, 84 at diametrically spaced positions to facilitate accurate setting of the knife relative to the calibrated scale or dial element 90 to be referred to later. Springs vertically housed in the head 83 as at 83a thrust between the head and the dial for frictional holding purposes, whereby the winged adjusting nut 80 and the dial 90 generally will turn as a unit but enabling independent turning of the dial for setting the zero mark of its scale as appropriate for the particular size of cable, as will later be more fully explained.

Referring to Fig. 1, the central bore of the turret 60 is enlarged at the upper end to provide a seat as at 69 for a ball bearing unit whereby the adjusting nut and dial pair 80, 90 are supported for free rotative movement relative to the turret 60 while prevented from axial movement, so as to adjust the knife 3 longitudinally. The ball bearing unit comprises an outer ring 85 received on the turret seat 69, and an inner ring 86 fitted on the lower tubular portion 81 of the adjusting nut 80. Said tubular nut portion 81 projects below the bearing and is there annularly grooved to receive a spring lock ring 87 preventing longitudinal displacement of the nut and the bearing. A plurality of set screws 88 extending through the wall of the turret near its upper end engage the outer ring 85 of the bearing unit to anchor it in the turret substantially as in Fig. 1. Since the lock ring 87 prevents upward withdrawal of the adjusting nut with respect to the inner bearing ring 86, and the latter is unitarily associated with the outer ring 85 through the ball bearing, the set screws 88 serve to retain the entire knife-adjusting assembly in operative position on the turret 60.

Referring now to Figs. 1, 2 and 6, the graduated dial or zero-setting element previously mentioned, indicated generally at 90, comprises a circular plate or dial proper 91 centrally apertured for reception on the tubular hub portion 81 of the adjusting nut 80, below the head 83 of the latter, and with capacity for turning relative to it when so desired.

The dial proper or plate 91 is of a diameter

preferably somewhat larger than the external diameter of the turret 60 so as to project beyond the turret for ready engagement by the operator's fingers. This independently adjustable dial element 90 includes a central depending collar 92 of a reduced diameter conforming substantially to that of the inner ball bearing ring 86 against which it has endwise seating engagement. As previously noted a number of springs 83a in the adjusting nut head bear on the upper face of the dial plate 91 so that these two parts tend to turn together. The lock ring 87 already mentioned holds the nut 80 and dial 90 against relative displacement in the upward direction.

As previously stated the major longitudinal portion of the knife bar or lead screw 70 is threaded; in a uniform manner, from a point adjacent the squared knife-holding portion to the opposite or upper end of the screw element. From the foregoing description it will be understood that by rotating the adjusting nut 80, by manually engaging its head 83 or wing extensions 84, 84, in one or the opposite direction the lead screw 70 and the knife 3 carried thereby are correspondingly shifted axially of the turret so as to project or retract the knife 3 as appropriate for the desired depth of cut. Desirably the arrangement is such that clockwise turning of the adjusting nut 80 as viewed in Fig. 2, in the instinctive "right-hand" manner for turning one threaded member down into another will lower the knife toward the cable. For such action the internal threading of the nut 83 is made left-handed and the external threading 75 of the knife bar is likewise left-hand. Hence "right-hand" turning of the axially immovable nut forces the knife downwardly with respect to the turret 60.

As best seen in Fig. 1, the overall length of the cutter blade or knife 3 and its holder bar 40 or lead screw 70 is substantially greater than the axial or vertical extent of the turret 60 and of the adjusting nut 80, to provide the desired range of adjustment for the knife and also to accommodate a locking means whereby the knife is securely held in any selected position of adjustment, subject to quick release. Such means herein comprises a sleeve-like locking nut 100 internally left-hand threaded at its lower portion as at 101 for cooperation with the left-hand knife bar threading 75, and having a knurled lateral flange or manipulating fingerpiece 102 by which it may readily be turned down against or released from the top face of the adjusting nut 83, to lock or unlock the latter with respect to the knife bar 70. Directive markings for the lock nut such as arrows and associated indicia "lock" and "unlock" may be provided in easily viewable position, as on the top face of the fingerpiece 102; see Fig. 2.

The adjusting nut 80 and the lock nut 100 desirably are yieldably connected so that the two will turn as a unit, in the unlocked position of the lock nut 100 and in either direction of knife-adjusting rotation of the nut 80. As herein shown such means, noting particularly Fig. 1, comprises a coil spring 105 surrounding the lock nut 100 below its flange 102 and having its opposite ends anchored respectively to the head 83 of the adjusting nut 80 and to the lock nut 100 as by means of pins or screws 106, 107 respectively.

The central bore at the upper portion of the lock nut 100, Fig. 1, above the manipulating flange 102, desirably is somewhat enlarged, the bottom wall of the enlargement providing a stop

shoulder as at 103 for engagement by a stop washer 77 removably held at the upper end of the knife bar 70 as by a screw 78. Thus the knife is afforded a limiting down stop and the lock nut is prevented from unintended dislodging from the knife bar. A protective cap 108 desirably is removably fitted onto the upper end of the lock nut 100, above its fingerpiece 102 and of a length to accommodate the knife bar within it in the maximum elevation of the knife.

In Fig. 1 the knife 3 is shown in a raised position in which it is substantially fully withdrawn into the housing and guiding channel therefore at the lower portion of the central bore of the turret 60. This position is representative of that for a cable of relatively small diameter such as indicated by the broken line circle C². The projecting lower end 60' of the turret 60, below the table 2 and the lock ring 64 is formed for seating and holding engagement with the work, in a plurality of different angular positions of the turret with respect to the table 2. In the illustrated example the turret is adapted to straddle the cable so as to present the knife 3 for cutting lengthwise the cable and optionally for cutting the cable transversely.

Accordingly, noting Figs. 1, 9 and 10, the projecting lower end 60' of the turret 60, of a generally cylindrical skirt-like nature centrally around and radially spaced from the knife position, is formed with trough-like inverted-V seating formations 601 and 602 in paired alignment along one diameter of the turret, and at right angles thereto with a corresponding pair of similar opposed formations 603 and 604. These seating formations of each pair are at opposite sides of the central knife position. The inclined down-flaring faces of each such formation, in the respective pairs, 601, 602 and 603, 604, are symmetrically disposed with respect to the vertical plane containing the knife and the axis of its supporting lead screw 70, and they stand in planes which intersect the plane of said axis along a common line. Thus each pair of cable-receiving formations such as 601, 602 or 603, 604 is adapted to help position the turret and its knife on a cable by engagement therewith at spaced positions along the cable and at opposite sides of the knife, ahead of and behind the latter and in the same vertical plane with the knife axis. Hence either pair 601, 602 or 603, 604 of guide formations, whichever is then operatively positioned in the fore and aft line of the tool, for longitudinal or transverse cutting respectively, is adapted to seat the cable vertically opposite the knife. It will be understood that such directional terms as "vertical" are herein used merely for descriptive purposes, and with reference to an upright position of the tool, such as in Fig. 1. In use the tool may be applied to present the knife in any desired plane radially of the cable.

With the turret in that position of angular adjustment about its axis as shown in Fig. 1, also Fig. 10, the operative plane of the knife coincides with a longitudinal plane through the cable axis, as appropriate for cutting the cable armor or sheath lengthwise. In such position the seating formations 601 and 602 are active. The other pair of like formations 603, 604 is adapted for similar seating engagement with the cable, but with the operative plane of the knife at right angles to that just above mentioned. That is, with the knife turret 60 turned 90° from the Fig. 1 position, to present the seat pair 603, 604 in the fore and aft line of the tool, the operat-

ing plane of the knife 3 thus is transverse of the cable, at substantially right angles to the cable axis. The two knife positions as referred to will be evident from a comparison of Fig. 1 and Fig.

8. In Fig. 8, assuming that the cable is seen in transverse section below the knife 3 similarly as in Fig. 1, the knife is viewed as if the turret had been rotated 90° from the Fig. 1 position. In other words, in Fig. 1 the knife is shown as positioned for longitudinal cutting; if now the turret is given a quarter turn from the Fig. 1 setting the knife would then appear in Fig. 1 positioned as in Fig. 8, for transverse cutting.

As previously described, adjustment of the turret and knife as between longitudinal or transverse cutting positions is effected merely by retracting the locking plunger 65, 66, Fig. 5 and rotating the turret 90° in either direction. On arrival of the turret at the desired new position the plunger automatically engages the corresponding one of the radial sockets 61a of the turret, thereby locking it in said position.

With reference particularly to Figs. 1 and 10, it will be seen that the described pairs of inverted trough-like cable-seating formations 601, 602 and 603, 604 of the turret will accommodate cable sizes over a substantial range, such as indicated by the smaller and the intermediate broken-line circles C² and C¹. For any particular size of cable the bed plate 1 and its cable-engaging roller 55 are adjusted relative to the turret and its supporting table 2 so that the periphery of the roller is brought into firm engagement against the cable and diametrically opposite the knife 3, in the same vertical plane with the latter in the upright position of the tool as in Fig. 1. This spacing adjustment as between the roll or bed plate 1 and the tool table 2 is effected in a manner already described with reference to the connector posts 4 and 5 and associated parts including the means for rapid sliding of the plunger-equipped block 30 to and relocking it in any selected position along post 5, and for corresponding rotative adjustment and locking of the clamping element 10 along the other and swingable post 4 subject to quick release by the latch 14.

Further in this connection, again noting Fig. 1, it will be apparent that the turret-like mounting for the cable-engaging roll 55 on its carrier 50 turnable on the bed plate 1 provides for cooperative parallel arrangement of the roller and of the knife, for either direction of cutting, that is, either lengthwise or crosswise of the cable. Thus the turret elements of the two work and tool locating plates 1 and 2 mutually cooperate in adapting the tool for plural-directional cutting. In the Fig. 1 position the turret 60 of table 2 is angularly disposed to present the knife 3 with its blade in an operative plane lengthwise the cable. Correspondingly the roller-carrying turret 50 of the bed plate 1 has been turned to and automatically locked by its spring detent 58 in an angular position presenting the roller 55 with its axis transverse of the cable, for cooperative rotation of the roller in the same plane with that of the knife and of the cable axis. For transverse cutting both the knife-turret and the roll-turret are turned 90°, the roller axis then paralleling the cable and the roller being presented in a position to rotate in a plane transverse of the cable so as to follow rotatively about and against the peripheral surface of the cable while the knife cuts the sheath or protective covering of the latter transversely.

75 For larger sizes of cables as for example up to

a diameter as indicated by the large broken-line circle C of Fig. 1, the device desirably is equipped with supplemental cable-guiding and positioning means, serving in effect as extensions of the inclined walls of the guide formations 601, 602 or 603, 604 carried by the turret. For classes of work for which the range in cable size is less extensive, and particularly as to the smaller models of my tool as a whole, such auxiliary work-positioning means may be omitted. In other instances, especially in the larger models of my cable slitting tool, and in any instance where it may be desirable to handle cables varying in diameter as widely as represented by the large and the small circles C and C² of Fig. 1, such auxiliary guiding and positioning means preferably is supplied. In this connection the construction and arrangement preferably is such that the supplemental guides may be demounted or installed as circumstances may require.

Accordingly, and referring now more particularly to Figs. 1, 5, 6 and 10, the upper plate or table 2 is adapted to support at its front and rear portions and centrally in line with the knife and the turret axis a pair of guide blocks 120, 121 depending from the table 2 and demountably secured to it as by screw bolts 122, 123. These blocks are formed with central down flaring inverted-V formations 124, 125 having their respective opposed inclined faces aligning with those of the holding formations 601, 602 or 603, 604 on the turret. Thus for the cable sizes, from those such as indicated by the small broken-line circle C², Fig. 1, up to that corresponding to the broken line circle C¹ of Fig. 1 these front and rear auxiliary elements 120, 121 provide, in cooperation with the aligned guide formations of the turret, positioning and guiding engagement for the tool with respect to the cable at four aligned locations distributed along it, two in advance of and two in the rear of, the working position of the knife 3.

For still larger cable sizes up to the maximum C of Fig. 1 the inclined guide surfaces of the guide blocks 120, 121 are in effect prolonged, and in a manner adapting them for low-friction engagement with the outer wall of the cable. Accordingly, noting Figs. 5, 6, 9 and 10, the sides of the blocks 120, 121 are bevelled off as at 126, 127 along inclined planes perpendicular to those of the opposed cable-engaging walls of the guide formations 124, 125 respectively. Projecting centrally from each of the pairs of inclined faces 126, 127 are bearing studs 128, 129 having their axes mutually perpendicular, at each of the blocks 120, 121, and paralleling the planes defined by the inverted-V formations 601, 602 or 603, 604 of the turret and 124, 125 of the respective blocks. Rotatably mounted on these stud pairs of each block are corresponding pairs of elongated generally cylindrical guide rollers 130 and 131, desirably having their lower or outer ends rounded as at 132, 133. These guide rollers 130 and 131 are of a diameter such that the opposed inner peripheral portions of the respective roller pairs are tangential to the extended planes of the inverted-V guide formations 124, 125 already described. Thus the roller pairs 130 and 131 constitute moving guide means ahead of and behind the knife in its longitudinal cutting position as in Fig. 1, adapted to seat on and to be travelled along the larger sizes of cables so as accurately to center and align the knife 3 with respect to such cables in the manner as will be evident in Fig. 1 as

considered with respect to a representative large cable C.

Again considering Figs. 6 and 9, these guide rolls 130 and 131 are held in operative position on their supporting studs as by bearing heads 128a, 129a at the outer ends of the studs, the inner ends of the latter being demountably fixed in the corresponding blocks 120 and 121 as by a driving fit or by threading into tapped recesses. Thus when 10 desired the extension guide rollers 130 and 131 may be dispensed with, leaving the blocks 120, 121 and their guide formations 124, 125 in operative position so as to afford the described aligned series of guide formations, four in this instance, 15 for engagement at a like number of locations along cables of the smaller and the intermediate sizes. For still other conditions, as when only relatively small cable sizes are to be prepared or in connection with smaller models of the tool as a whole, the blocks 120, 121 themselves may be 20 temporarily or otherwise discarded, centering and guiding of the work with respect to the knife being accomplished by the guide means directly on the turret 40 itself.

In the operation of my cable preparing tool it will be understood that the same is installed in operative position upon the cable in the manner as represented in Fig. 1 and as already fully explained in connection with the description of the 25 adjustable and the quick detachable positioning and clamping means associated with the connector posts 4 and 5 and the lower and upper plates 1 and 2. As thus installed on the work, as for example in association with a relatively large cable C of Fig. 1, it will be understood that the cable extends in the fore and aft direction, toward and from the viewer in Fig. 1, through the work space defined by and between the upper and lower plates 1, 2, and their spacing connections 4, 5 and associated parts. The knife 3 having been adjusted for the appropriate depth of cut, the tool is then moved along and upon the cable over whatever length thereof there is to be slitted for stripping of the cable armor or sheath. Movement of the tool with respect to the cable 40 may be continuous in one direction, either toward or away from the free end of the cable as the operator may find more convenient. In this connection it is noted, particularly with reference to Fig. 8, that the cutting instrument or knife proper 45 3 preferably is formed with a double edged and herein oppositely slightly concaved bevelled cutting edge, as at 3b, 3b symmetrically disposed and merging into a somewhat rounded puncturing and cutting edge formation 3c at the lower end. Thus 50 the tool is adapted for cutting in either direction.

In thus manipulating the tool it may be manually engaged directly at the opposite side portions of the knife table 2, the posts 4 and 5 being available as convenient gripping means, as evident in 55 Fig. 1. If desired, other and preferably detachable grip means may be provided at the respective sides of the tool, as illustrated for example in Fig. 5. For this purpose the pivot pin 31 for the adjustable slide block 30 at the right side of the 60 tool, Figs. 1, 3 and 5, is extended in the fore and aft direction beyond the divided bracket portion 28, 29 of the plate 2 sufficiently to provide pivotal mounting for a U-shaped handle 136, the spaced legs 137, 137 of which are apertured for pivotal 65 reception on the pin 31. The spring grips or rings 32 on the pivot pin 31 as previously described permit the handle to be detached when not desired for use. A similar grip and handle element 138 is provided at the opposite or left side of the 70 tool, Fig. 5, having its legs 139, 139 pivotally and

demountably received on individual studs 140, 141 threaded or otherwise demountably fixed in aligned recesses for the purpose in the corresponding lateral portion of the upper plate or table 2, at the opposite sides of the clamp-receiving slot 8 therein.

Referring again to Fig. 1, also Figs. 2 and 6, the construction, arrangement and manner of operation of the precision setting means for the knife will now be apparent from the foregoing description. As positioned in Fig. 1, the knife 3 is at or near maximum elevated or retracted position, in which its cable entering point 3c (Fig. 8) extends but little into the mouth or apex of the inverted trough-like guide formations described. This corresponds to a preliminary positioning of the knife as appropriate for a small cable such as C² of Fig. 1. For the purposes of explanation, assume now that the tool is to be employed for longitudinally slitting the outer armor or sheath of such relatively small cable C². From the manufacturer's data or from training and experience the worker determines that for this particular size and type of cable the appropriate cut depth for stripping the outer protective element of the cable is 0.030 in. The tool is installed about the cable, the bed plate 1 and the tool table 2 being adjusted to and locked in a position of relatively close approach to each other, in which the work-supporting roller 55 of the lower plate disk 50 is centrally in contact with the under peripheral portion of cable C² of Fig. 1. The knife adjusting nut 80, being first released by unlocking turning of the lock nut 100 in the direction of the arrow so marked in Fig. 2, the adjusting nut 80 is now turned in the knife lowering direction (in the natural right-hand or clockwise direction) until the point 3c of the knife 3 just engages the top surface of the cable C². By reason of the described construction and arrangement of the parts including the anti-friction ball bearing means described, the knife adjustment is afforded such sensitivity that contact of the knife onto the cable is easily felt by the operator. For this purpose the periphery of the graduated disk element 90, Figs. 1, 2 and 6, is knurled. By brushing the ends of the fingers along this periphery an exceedingly accurate zero setting may be obtained. This preliminary non-piercing positioning of the knife may also be checked visually by sighting from either side of the knife at the apex of the V-guide formations; Fig. 9. In making this preliminary adjustment the relative position of the graduated dial element 90 is immaterial.

In the selected example, the appropriate cutting depth has been assumed as 0.30 in. Consider now particularly Figs. 1, 2 and 6, for setting the knife for such cut depth and in association with the given cable size C², the graduated dial 90 is now independently turned to bring its zero mark opposite an index or pointer provided for the purpose, the unlocked adjusting nut 80 being at this time manually held against turning as by positioning of a finger against one of the nut wings 84. The dial setting index is seen generally in plan at 150 in Fig. 2 and in front elevation in Fig. 6. It is herein conveniently located at the upper front portion of the turret 60 and comprises an upright pointer 151 opposite or adjacent to the edge of the dial 90 so as to be easily readable against the latter. It is secured to the turret 60 in any convenient manner as by means of a small arcuate plate 152 having the pointer 151 integrally or otherwise fixed to it, the plate being

removably secured to the outer cylindrical upper wall portion of the turret as by screws 153, 153.

As best seen in Fig. 2, the dial 90 is accurately calibrated with reference to the interengaging 5 thread formations of the adjusting nut 80 and the lead screw or holder bar 70 for the knife. Merely by way of example, the lead screw and adjusting nut threading may be of $\frac{7}{16}$ in. diameter and 20 threads to the inch, that being, in an 10 average size of my tool, a convenient threading for affording the desired sensitivity and precision of knife adjustment through extremely small increments, as for example of the order of 0.001 in. in the illustrated example, giving a 15 range of selective setting for one turn of the dial from zero to 0.050 in. by available increments of 0.001 in.

The scale 90a, Fig. 2, concentrically arranged about the upper marginal portion of the dial 90 is represented as graduated into 50 equal increments and the calibration is such that each individual spaced mark of the scale 90a represents precisely 0.001 in. of vertical adjustment for the knife 3. Numerical and preferably other indicia 20 are herein associated with the scale 90a. In the example of Fig. 2, the 10's of units are indicated by the numerals 10, 20, 30 and 40, from and around to the zero mark which also represents the total of 50 units. The group of 10 units may 25 be further divided into 5's, as by elongation of each 5th individual unit mark. Since it is frequently necessary in connection with cable installation to work in poorly lighted locations, or in which the particular location of the cable hinders 30 visual reading of the dial, provision is desirably made for setting the dial by touch. For this purpose, besides being knurled for sensitive adjustment, the edge of the dial 90 has distinguishing formations, notches, projections or the like 35 corresponding to the zero mark and preferably at least at 10's of units. As seen in Fig. 2, the dial margin opposite the zero marking has a distinctive modification such as a group of three notches 90°, while opposite the 10, 20, 30 and 40 marks the 40 dial has single notches or other means as at 90°, 90², 90³ and 90⁴. The zero setting is thus readily 45 identified and also distinguished from the 10's locations by the operator's finger feeling against the triple notching 90°, the 10's settings also being 50 identifiable by touch.

Returning to our particular example of a selected cut-depth setting of 0.030 in., the knife blade has been contacted with the cable, and the dial 90 has been turned, independently, to set the 55 zero thereof opposite the pointer or index 151, by the medium either of the visual or the sensory means or both. Note that in said independent turning of the dial the knife blade is not moved, but remains at the cable surface. Now the operator has only to turn the adjusting nut 80 and the dial 90, as a unit and in the direction of increasing values on the dial scale, to bring the selected depth value of the scale to a position opposite the pointer 151. This depresses the knife 60 blade 30 units of the scale, in other words 0.030 in. in the illustrative example, for making a cut of 65 that depth.

The unit turning movement of the adjusting nut and the dial is effected by manually engaging the nut, conveniently by its wings 84—84, the dial automatically following by reason of the described frictional holding relation of the parts as insured by the springs 83a, Fig. 1.

In our example the setting sought is 0.030 in. 70 Hence, to make the above knife-depressing ad-

justment to that value, the nut-and-dial unit 30—99 is turned right-handed by the nut wings 84—84 until 30 units have reached to the pointer 151 of Figs. 2 and 6. Point 98³, Fig. 2, will then be opposite said pointer. The knife blade has thereby been depressed into the cable for a distance of precisely 0.030 in. On locking of the blade the precision-calibrated tool is ready for stripping the cable of its armor.

Locking is effected, in the accurately set position of the blade, merely by giving the locking nut 100 a partial downward turn, in the direction of the arrow and associated word "lock," Fig. 2. Stripping of the cable can then be rapidly performed without further calculation or attention on the operator's part to the depth of cut, merely by moving the tool along the cable in the manner already described.

From the foregoing description in connection with the drawings it will be understood that with my precision calibrated tool stripping of the armor or sheath from the cable of any size and type within the range of the particular size of tool may be speedily accomplished, with an accurate and predetermined depth of cut as appropriate for the given job. The frame clamping means including the quick-releasing latch affords easy installation of the tool on the cable of whatever size. The precision setting of the blade, with the correct cut depth known, is rapidly available by manipulation of the adjusting nut and dial means, and involves only the unlocking by the nut 100, the lowering of the blade by the nut wings 84—84, the separate zero-setting of the dial element 98, and the setting of the nut-and-dial unit to the desired cut-depth value and relocking thereat. With but little practice even the relatively inexperienced cable man is thus enabled to perform satisfactory work in a quick and easy manner.

Cable manufacturers specify thickness dimensions for the armor or sheath and other parts sometimes in decimals and sometimes in the ordinary fractions such as $\frac{1}{8}$, etc. In the interest of accuracy and as an additional convenience and aid to rapid work, a conversion table desirably is located on the tool, as shown for example on Fig. 5 at the central rear portion of the upper face of the top table 2. Such conversion table as there indicated may contain the fractions of inches more frequently met in determining the depth of cut, with the decimal equivalents set opposite them.

Below the armor and the impervious sheath of some cables there are one or more coverings on the lay of the cable, that is, on the group of individually insulated conductors and the associated filler means. Such other coverings frequently need to be cut to give easy access to the individual conductors. If the initial cut through the armor and sheath of such electric cable is not quite deep enough, it leaves the interior or lay of the cable difficult of access. On the other hand, if the cut is too deep it is likely to injure the insulation of the individual conductors. Thus, frequently a few thousandths of an inch forms the allowable tolerance for the cut. Such requirements are satisfied in accordance with the present invention, my precision cable knife combining micrometer cut-depth settings in whatever units are desired with speed and dependability in operation as well as a maximum of safety to the user.

Accordingly, from a consideration of the illustrative embodiment of the invention as herein disclosed, it will be apparent that the precision

setting of the knife, installation of the tool upon any given piece of work, and performance of the particular cutting operation, whether longitudinal or transverse of the cable, may readily be accomplished for a wide range of sizes and types of cable even by workers having little or no experience or acquired skill in this field.

My invention is not limited to the particular embodiments thereof illustrated and described herein, and I set forth its scope in my following claims.

I claim:

1. A stripping knife for electric cables comprising in combination, positioning plates spaced to receive a cable between them, plate connecting means including spaced posts, one post fixed at one end relative to one of the plates and having adjustable sliding and locking engagement with the other plate, the other post pivoted at one end to one plate and having means affording adjustable clamping engagement thereof with the other plate, a cable-engaging roller on one plate and a knife head oppositely disposed on the other plate, an elongated knife element mounted in the head with capacity for longitudinal adjustment toward and from the roller, a manual adjusting member rotatable on the head and held thereby against axial movement, and threaded connections between the knife element and the adjusting member whereby turning of the latter projects or retracts the knife element for predeterminedly setting the depth of cut.
2. A stripping knife according to claim 1 in which the cable-engaging roller and the knife head are angularly adjustable about a common axis to change the direction of cut relative to the axis of the cable.
3. A stripping knife according to claim 1 including stop means positively limiting the maximum projection of the knife element relative to the head and adjusting member.

4. A precision tool for stripping electric cables comprising, in combination, upper and lower positioning plates, parallel uprights connecting the plates in adjustably spaced relation, a knife carrier head on the upper plate having a central bore of which at least a portion is of non-round section, an elongated knife element having a portion conformant to and guided in the bore of the head, a manual adjusting member rotatively mounted on the head and held against relative axial movement, threaded connections between the knife element and the adjusting member operative to raise or lower the knife element by rotation of the adjusting member, and selective setting means including a dial calibrated in units of knife movement and a cooperable index, the dial and index being relatively rotatable with respect to each other, one of them being rotatable with the adjusting member and the other being on the knife carrier head.
5. A precision tool according to claim 4 including locking means comprising a lock nut on the knife element adjacent the adjusting member and means causing the lock nut and the adjusting member to turn together when unlocked.
6. A precision tool according to claim 4 in which the dial is constructed and arranged to be turned independently of the adjusting member to set the zero calibration opposite the index for different initial positions of the adjusting member.

7. In a cable-stripping knife, a positioning frame comprising spaced plates having connecting posts, the posts having corresponding ends

secured to one plate and being adapted for attachment to the other plate at variable positions along the posts, at least one of the posts having its secured end pivoted to said first plate for lateral swinging movement to open and close the frame and having screw clamping and quick-releasable latch means cooperatively engageable with the other plate.

8. In a cable-stripping knife according to claim 7, the construction wherein the pivoted post has a clamping nut threaded on it, the nut including a collar and a head, said other plate being slotted to receive the collar, and the latch means comprises a lever pivoted for movement in the plane of said other plate and recessed in opposition to the plate slot, whereby the lever is pivotally movable to and from a clamping position between the plate and the nut head in which the lever recess receives the nut collar.

9. In a cable-stripping knife according to claim 7, the construction in which the screw clamping means includes an adjusting nut threaded on the pivoted post to overlie the adjacent plate, a lock nut on said pivoted post beyond the adjusting nut and means causing one nut to follow the other in unlocked turning thereof.

10. In a cable-stripping knife, a knife carrier plate and an opposite cable-positioning plate, a pair of posts for connecting the plates in adjustable spaced relation, one post pivoted at one end to one plate, said pivoted post having quick-releasing adjustable connections with the other plate, said connections including a clamping nut threaded on the post, a latch lever pivoted on said other plate to swing in the plane thereof to and from clamping position, cooperative oppositely open recesses in the lever and said other plate to receive the portion of the pivoted post adjacently below the nut, and interengageable cam formations on the lever and the clamping nut facilitating entry of the lever beneath the nut and whereby the lever in moving to clamping position draws the plates toward each other and into pre-set holding relation to a cable passing between them.

11. In a cable-stripping knife, a positioning frame comprising spaced plates having posts for connecting them in variably spaced relation, the posts having corresponding ends secured to one plate and adapted for attachment to the other plate at variable positions along the posts, one of the posts fixedly secured to one plate and having a longitudinal flat face presenting a series of locking recesses, a plunger-carrying block slidably associated with said post and pivotally connected to said other plate, and a spring-pressed plunger housed in the block for selective holding engagement with any recess of said series.

12. In a cable-stripping knife according to claim 11, the construction wherein the plunger and block have interengageable cam means assisting movement of the plunger to locking position, and alternatively interengageable means to hold the plunger in retracted unlocking position.

13. In a cable-stripping tool, a cutting blade, a blade-holding head, a positioning frame adapted to surround the cable, said head mounted on the frame with capacity for angular adjustment to present the blade for action lengthwise or transverse of the cable selectively a cable-engaging wheel, and a carrier rotatably presenting the wheel opposite the blade, the wheel carrier

being rotatably supported on the frame for bodily shifting the wheel to conform its plane of rotation to the direction of blade action.

14. In a cable-stripping tool, a positioning frame adapted to surround the cable, a turret-like knife head angularly movable on the frame, a cable-engaging wheel, a carrier on the frame rotatably presenting the wheel opposite the knife head and itself angularly movable coaxially with the knife head, and manually releasable automatically engaging means for holding the knife head and the wheel carrier in the selected and relatively conformant angular positions with respect to the cable axis.

15. In a cable-stripping tool, a tool positioning frame comprising opposed plates adapted to receive a cable between them, laterally spaced posts for adjustably connecting the plates in cable-receiving position, one post being pivotally connected to one plate for outward opening movement to admit the cable between the plates, and spring means urging said post toward closed engagement with the other plate.

16. In a cable-stripping tool, a positioning frame to surround a cable, said frame including a plate mounting a knife head, a knife centrally carried by the head for cutting into a cable within the frame, said head being angularly adjustable on the plate in the manner of a turret and having an inner portion extending through the plate, said inner head portion having a plurality of pairs of cable-seating formations arranged along different diameters of the head and respectively engageable with the cable in different positions of angular adjustment of the head.

17. A cable-stripping tool according to claim 16 and including in combination other cable-seating formations on the tool frame in a plane radial of the head for positioning engagement with larger sizes of cable.

18. A cable-stripping tool comprising a cable-surrounding positioning frame, a knife-holding head on the frame, an elongated knife element carried by the head with capacity for projection and retraction relative to it to give different depths of cut, an adjusting member rotatably and non-axially movable on the head, threaded connections between the adjusting member and the knife element, and a depth value selecting dial rotatable on the head coaxially with the adjusting member and adapted at times to turn as a unit with the latter and at times to be turned independently thereof, and zero to maximum depth-calibrated scale and index means associated with the dial and with the head, whereby the knife element may initially be set to contact the surface of the given cable, the dial may then be turned to a zero setting of the scale and index means, and the adjusting member and dial may thereon be turned as a unit to pre-select the appropriate known cut-depth setting of the knife element for said given cable.
